(57) **CLAIM**

The ornamental design for a pillow with rod-shaped insert, as shown and described.

DESCRIPTION

FIG. 1 is a top rear left perspective view of a pillow with rod-shaped insert;

FIG. 2 is a bottom front right perspective view thereof;

FIG. 3 is a side elevation view thereof, the opposite side being a mirror image;

FIG. 4 is a front elevational view thereof, the rear side being a mirror image;

FIG. 5 is a sectional view along the section line 5-5 of FIG. 6;

FIG. 6 is a top plan view thereof; and,

FIG. 7 is a bottom plan view.

The portions of the pillow with rod-shaped insert, shown with stippling, illustrate areas of contrasting appearance.

1 Claim, 5 Drawing Sheets
